UNITED STATES PATENT OFFICE.

THOMAS H. BRENNAN, OF CHICAGO, ILLINOIS.

CONSTRUCTION FOR RADIO RECEIVING INDUCTANCES.

Application filed April 27, 1925. Serial No. 26,025.

My invention relates to a construction for radio receiving inductances, designed especially to minimize energy depletion through dielectric absorption and leakage in the inductances preceding the tube and to increase 5 selectivity, range of reception and as well to improve clarity of tone, and the main object of my invention is the provision of an improved receiver of this character which 10 will be economical in manufacture and highly efficient in use.

Other objects will appear hereinafter.

The invention consists in the combinations and arrangements of parts hereinafter described and claimed.

The invention will be best understood by reference to the accompanying drawings, forming a part of this specification, and in which,

Fig. 1 represents a side elevational view of my improved construction for receiving inductances;

Fig. 2 represents a central cross sectional view taken on the line 2—2 of Fig. 1;

Fig. 3 is a front end view, taken on the line 3—3 of Fig. 1, parts being shown in section;

Fig. 4 is a rear end view, taken approximately on the line 4—4 of Fig. 1;

Fig. 5 is a fragmental front elevational view;

Fig. 6 represents a central vertical section, taken approximately on the line 6—6 of Fig. 5, the secondary winding and supporting frame therefor being only partially shown;

and

Fig. 7 represents a cross section taken on the line 7—7 of Fig. 6.

With more particular reference to the parts illustrated in the accompanying drawings, the numeral 8 denotes a secondary coil wound in cylindrical form, the windings thereof being held and embraced at intervals by pairs of crossing members or strips 9 made of any suitable insulation material, preferably of bakelite. The extremities of these insulation crossing strips are bolted upon end supporting rings 10 and 11 as best illustrated in Figs. 1 and 2. This secondary coil 8 is thus embraced by the spaced apart 40 pairs of crossing members 9 which afford the only solid dielectrics contacting with the windings thereof, it being observed that this coil is thus supported on and spaced from the end rings 10 and 11. This secondary 45 coil and its mounting is more fully illustrated and described in the application of

Andrew F. Henninger Jr., for Letters Patent of the United States, filed August 11, 1924, Serial No. 731,361 which became Letters Patent No. 1,551,392, dated August 25, 1925.

According to the preferred embodiment of my invention as illustrated in the accompanying drawings, the secondary coil 8 is supported in inclined position and upon an angular bracket 12 which, as best shown in Fig. 6, is threaded upon a sleeve member 13 between a bushing 14 and a securing nut 15, both of which are threaded upon said sleeve 13. The bushing 14 is arranged in a panel board 16 or other suitable support. Extending through and rotatable in the sleeve 13 is a shaft 17 to which is secured on the outer side of the panel 16, a turning knob 18 carrying the usual dial member 19. To the inner protruding end of the shaft 17 is secured an angular bracket 20 carrying a pair of insulation strips 21 which cross and embrace the windings of the primary coil 22. The insulation strips 21 are preferably made of bakelite and one of these strips is suitably grooved at 23 to provide a channel for the reception of the windings of the coil, which said windings are held rigid in properly wound relation by the clamping action of said strips. For securing the strips 21 together in proper clamping relation, I preferably pass bolt members 24 therethrough, to which bolt members are applied the usual adjusting nuts 25.

Under this arrangement, the primary coil 22, which is of less diameter than the secondary coil 8, is supported for movement and angular adjustment within the windings of the secondary coil 8; and owing to the angular relationship between the secondary coil 8 and the position of the rotatable shaft 17, the angular bracket 20 so supports the primary coil 22 that the same upon the turning of the shaft 17 may be moved from a position in which it is concentric with the secondary coil to a position in which it is at right angles to the windings of the said secondary coil. It being unnecessary to move the primary coil more than 180 degrees or from a position concentric with the secondary coil to a position at right angles therewith, I preferably provide means for limiting the turning movement of the rotary shaft 17. This limiting means comprises a pin 26 on the shaft 17 and a circumferentially extending slot 27 in the sleeve 13, the

said pin being adapted to work in said slot and to engage the end walls thereof as abutments whereby to limit the turning of the shaft. The free ends of the coil 22 are taken 5 rearwardly through the secondary coil 8 and secured to suitable soldering lugs 28 as best illustrated in Fig. 3.

It will be observed that the primary coil 22 is entirely open to the air except at the 10 points where it is confined by the crossing strips 21. By this construction I provide a minimum of solid dielectric and a maximum of atmospheric dielectric, thereby reducing losses by absorption and leakage to 15 a minimum while providing a clear space for the maximum transfer of energy. In this connection, it is also to be observed that no shellac, varnish, cement or other compound is used to hold the coil since the 20 windings thereof are rigidly held in proper position by the crossing strips 21.

Secured to the rear ring 11 is a hinge member 29 carrying insulation strips 30 which cross and embrace a tuning inductance or coil 31. This tuning coil, like the primary coil is entirely open to the air except at the points where it is confined by the crossing strips 30. The coil 31 is of less diameter than the secondary coil 8 and owing to its hinged engagement with the ring 11 it may be moved into various positions of adjustment with respect to the secondary coil. The ends of the coil 31 are brought to 30 suitable soldering lugs 32.

35 From the foregoing description taken in connection with the accompanying drawings, it will be understood by those familiar with radio receiving sets that I have not only provided a very simple inductance construction, 40 in which air alone is the dielectric except at the points where the windings are embraced by the crossing strips, but one that provides for a maximum transfer of energy through the coils preceding the detector, whereby to 45 increase the range of reception, volume and improve the clarity of the tone.

While I have illustrated and described the preferred form of construction for carrying my invention into effect, this is capable of 50 variation and modification without departing from the spirit of the invention. I, therefore, do not wish to be limited to the precise details of construction set forth, but desire to avail myself of such variations and

modifications, as come within the scope of 55 the appended claims.

Having described my invention, what I claim as new and desire to secure by Letters Patent is:

1. In a construction for radio receiving inductances, the combination with a bracket member, of a shaft having rotatable support in said bracket member; an insulation member carried by said shaft; a coil having its winding held by and positioned on said member and otherwise open to atmospheric dielectric; a second coil surrounding the first named coil; means for insulatively supporting the second named coil from said bracket member; an insulation strip hinged to said supporting means; and a third coil having its winding held by said hinge strip and adapted to be swung into various positions of adjustment with respect to said second named coil, substantially as described. 60

2. In a construction for radio receiving inductances, the combination with a bracket member, of a frame including insulation strips carried by said bracket member; a cylindrical coil having its winding held on 65 said insulation strips; an insulation strip hinged to said frame; and a coil having its winding held by and positioned on said hinged insulation strip and otherwise open 70 to the air as a dielectric and adapted to be 75 swung into various positions of adjustment with respect to said first named coil, substantially as described. 80

3. A construction for radio receiving inductances including a frame provided with 90 end pieces; a cylindrical coil carried by the frame between the end pieces; a bracket attached to one end piece and provided with a bearing; a shaft rotatable in said bearing; an insulation support projecting from the 95 shaft inwardly of the frame; a coil having its winding mounted on said insulation support and adapted to be adjusted within the first named coil; an insulation support hinged to the other end piece; and a third 100 coil having its winding mounted on said hinged support for movement in relation to said first named coil, substantially as described. 105

In testimony whereof I have signed my name to this specification.

THOMAS H. BRENNAN.
